UNITED STATES PATENT OFFICE.

OTTO SIEGLER AND EUGENE G. SIEGLER, OF BELLEVILLE, ILLINOIS.

GAS-RANGE BURNER.

Application filed March 29, 1924. Serial No. 702,734.

This invention relates to an improvement in gas range burners in which the primary object thereof is to provide an improved combined broiler and oven burner.

- 5 Another object of the invention is in providing a gas burner with improved means whereby the flames of the burning gas from the burner will be directed both upwardly and downwardly, the upwardly directing flames acting more directly upon the oven of the gas range, whereas the downwardly directing flames will act more directly upon the lower arranged broiler oven of the gas range.
- 10 15 A further object of the invention is in disposing portions of the gas burner in positions peculiar to the upwardly extending heat flues of the oven.

A still further object of the invention is in providing an improved form of oven bottom having a co-operable relation with this improved burner.

Other and further objects will appear in the specification and be specifically pointed out in the appended claims, reference being had to the accompanying drawings, exemplifying the invention, and in which:—

Figure 1 is a horizontal section taken through the oven of a gas range showing this improved gas burner and oven bottom mounted in operable relation thereto.

Figure 2 is a vertical section taken on the line II—II of Fig. 1.

Figure 3 is a fragmentary horizontal section taken through a portion of this improved burner.

Figure 4 is a fragmentary vertical section taken on the line IV—IV of Fig. 1.

Referring by numerals to the accompanying drawings, 1 designates the side walls of a gas-range oven, 2 the end wall and 3 the front wall or oven door, said walls providing the oven 4.

Horizontally disposed within the oven 4 is a removable oven bottom 5, said bottom 5 being supported at its inner end on the bracket or ledge 6 which is secured to the end wall 2, the forward end of the bottom being supported upon the brackets such as 7.

50 The oven bottom 5 is provided on each side with an upturned flange 8, and for reinforcing each of said flanges is a stiffening member 9, each being secured to a respective flange by the bolts 10. Each of the stiffening members 9 is provided with a foot 11 at each end which rests upon the bottom

proper of the oven bottom 5 as shown in Figs. 1 and 3.

Arranged beneath the oven bottom 5 is the improved burner 12, said burner being comprised of a pair of spaced apart longitudinally extending hollow legs 13 which are closed at each end and joining said legs is a pair of transversely disposed spaced apart hollow legs 14, said legs 14 being arranged intermediate of the length of the legs 13. Communicating with one of the hollow legs 13 is a gas supply neck 15, said neck engaging with the said leg 13 midway of its length as shown in Fig. 1.

The burner 12 is supported in position beneath the oven bottom 5 by a pair of transversely disposed rods 16 which are supported at their ends in brackets 17 which are secured to respective side walls 1, each of said rods engaging beneath the hollow legs 13 of the burner and are disposed between respective depending lugs 18 which are formed in the under side of said hollow legs 13.

Secured to each of the inner linings 19 to the side walls 1 are a series of horizontally disposed ledges 20, said ledges being disposed on a plane beneath the burner 12 and are for the purpose of supporting the broiler pan 21 in a selective position.

Arranged above the oven bottom 5 and in vertical alinement with each of the stiffening members 9 of said bottom is an inner wall 22 each bearing a series of shelf ledges 23 for the reception of a removable oven shelf not shown. The lower extremity of each inner wall 22 is held a distance above each of the stiffening members 9 thereby providing a passageway 24 beneath each of the walls 22 which provides communication above the bottom oven 5 for the products of combustion thereabove. Each of the inner walls 22 is disposed a distance inwardly from the lining 19 thereby providing vertical extending flues 25 which lead to the top of the oven.

The hollow legs 13 of the burner 12 are each provided with a series of outlet openings 26 which are arranged so as to direct the flame of the burning gas upwardly and outwardly in the direction as indicated by the arrows 27 in Fig. 2. It is to be noted that each of the legs 13 is arranged adjacent a respective side of the oven bottom 5 so that the gas flame will engage the oven bottom adjacent respective sides wherein the flames will be deflected from the bottom and

directly into respective vertical flues 25. This is for the purpose of directing most of the heat units upwardly as against heretofore directing of the heat units against the oven bottom centrally thereof thereby eliminating the warping of the oven bottom on account of the gas flames not permitted to traverse the entire oven bottom.

The hollow legs 14 of the burner 12 are each provided with a row of inwardly and downwardly directing gas emitting openings 28 which are adapted to direct the gas burning flames towards the broiler pan 21 in the direction of the arrow 29.

15 So that a uniform amount of gas will be provided to all of the hollow legs 13 and 14 of the burner, improved means are provided within the burner, said means being comprised of a centrally disposed deflecting portion 30 which is arranged to receive and divide the gas from the supply neck 15 to respective oppositely disposed portion 13^a of one of the hollow legs 13. An extending lip 31 is projected within each of the passage-
20 ways of the portions 13^a from a respective hollow member 14, each of said lips 31 directing the gas into each respective hollow member 14 and formed in the other hollow member 13 is a pair of deflecting portions 32 each being arranged in alinement with the discharging end of a respective hollow leg 14 and are adapted to direct the gas to the last mentioned hollow leg 13 and to the extending portions 13^b thereof.

35 In the operation of a gas range burner of this improved character, when a gas supply is provided within the supply neck 15 of the burner 12, the deflecting portion 30 will divide the gas entrainment and cause it to be forced into the portions 13^a of one of the hollow legs 13, the gas from the hollow leg 13 being acted upon by the respective deflecting portions 31 in which a gas entrainment will be forced in to each of the 40 transversely disposed hollow legs 14 and as the gas reaches the end of each of the hollow legs 14, the deflecting portions 32 will divide the entraining gas as it leaves each of the hollow legs 14 and force the gas into the other hollow leg 13 and into the extremities 13^b thereof.

The gas supply emitting from the burner upon being ignited will produce flames which are directed both upwardly and downwardly, the upwardly directing flames being provided by the upwardly and outwardly discharging openings 26 which are provided in the pair of hollow legs 13, the gas flames from said openings after engaging the oven bottom 5 adjacent the side edges thereof being immediately deflected off the oven bottom on account of the angular arrangement of the discharge openings 26, the gas flames after being deflected off the oven bottom entering directly into

respective vertical flues 25 which lead upwardly to the top of the oven and are deflected by the oven top not shown, back into the oven above the oven bottom 5.

Owing to the flames from the hollow legs 13 engaging only the outer portions of the oven bottom 5, said portions of the oven are relieved of warping on account of the upwardly bent flanges 8 being reinforced by the reinforcing members 9 and furthermore, on account of the flames from the hollow members 13 engaging only the outer portions of each side of the oven bottom 5, said bottom is relieved of being subjected to the extreme heat heretofore given to oven bottoms where the burner provides the flame to the entire oven bottom which creates a burning action to food stuffs arranged thereabove in the process of baking. This improved manner of allowing only the outer portion of the oven bottom to be engaged by the gas flames and afterwards immediately directing the flames and heat therefrom upwardly into the vertical flues 25 creates more of a uniform heat throughout the oven.

Flames created by the burning of the gas as it is emitted from the downwardly and inwardly directing openings 28 of the transverse hollow legs 14 will cause the heat to be directed downwardly towards the broiler pan 21 arranged below the burner 12, said flames not only being prevented from engaging the central portion of the oven bottom 5 but in addition thereto directing the flames and consequent heat therefrom towards the broiler pan where it is most desired. After the heat units have become confused above the broiler they will ascend upwardly in the flues 25 and become effective in the oven 4.

From the aforesaid description of this improved invention, it is obvious that a gas range of great efficiency is provided.

What we claim is:—

1. A gas burner for a range comprising a pair of spaced apart paralleling hollow legs each having a row of upwardly inclined discharge openings, each of said rows of openings being inclined outwardly from each other, and a pair of transversely disposed hollow legs joining with said other pair of hollow legs each being provided with a row of downwardly and inwardly directing discharge openings.

2. A gas burner for a range comprising a pair of spaced apart paralleling hollow legs, a pair of transversely disposed hollow legs adjoining and communicating with said first mentioned hollow legs, each of said legs being provided with a row of discharge openings, each row of openings of said first mentioned legs being arranged so as to direct upwardly and outwardly from each other, each row of openings of said transversely disposed legs being inclined down-

wardly and inwardly towards each other, and a gas supply neck communicating with one of said first mentioned hollow legs between the adjoining positions of said trans-

versely disposed legs thereto.

3. A gas burner for a range comprising a pair of spaced apart paralleling hollow legs each having a row of upwardly inclined discharge openings, each of said rows

10 of openings being inclined outwardly from

each other, a pair of transversely disposed hollow legs joining with said other pair of hollow legs each being provided with a row of downwardly and inwardly directing discharge openings, and a deflecting portion 15 related to each leg of said second mentioned pair of legs.

OTTO SIEGLER.
EUGENE G. SIEGLER.
